UNITED STATES PATENT OFFICE

EDWARD KANTER, OF CLEVELAND HEIGHTS, OHIO

DESIGN FOR A DISPENSING MACHINE CASING

Application filed July 14, 1931. Serial No. 40,540. Term of patent 14 years.

To all whom it may concern:

Be it known that I, EDWARD KANTER, a citizen of the United States, residing at Cleveland Heights, in the county of Cuyahoga and State of Ohio, have invented a new, original, and ornamental Design for a Dispensing Machine Casing, of which the following is a specification, reference being had to the accompanying drawings, forming part thereof, wherein Fig. 1 is a front elevation, Fig. 2 is a side elevation, and Fig. 3 is a top plan view of a dispensing machine casing illustrating my new design.

I claim:—

The ornamental design for a dispensing machine casing, as shown.

EDWARD KANTER.
